UNITED STATES PATENT OFFICE.

HARRY MINTZ, OF BOSTON, MASSACHUSETTS.

COUCH HAMMOCK.

1,414,432.

Specification of Letters Patent.

Patented May 2, 1922.

Application filed April 23, 1921. Serial No. 463,897.

To all whom it may concern:

Be it known that I, HARRY MINTZ, citizen of the United States of America, and resident of Boston, in the county of Suffolk and 5 State of Massachusetts, have invented new and useful Improvements in Couch Hammocks, of which the following is a specification.

This invention relates to hammocks and 10 more particularly to that type of hammock commonly called "couch" or "Gloucester" hammocks comprising essentially a rigid spring-carrying seat frame adapted to support a mattress or cushion, end and back 15 members of canvas or other suitable textile material and flexible suspension or supporting members.

Hammocks of this type which, as is well known, were originally adapted and intended 20 for use merely as porch swings, have now come to be regarded as indispensable articles of furniture in many situations such as upon carefully furnished protected verandas or in 25 closed rooms such as sun porches or the like 30 where an out-of-doors atmosphere or environment is desired. To meet these conditions of service it is essential that the hammock shall not only provide a very comfortable seat but shall be of such construction 35 as to permit it to be made of materials which will harmonize in texture and colors with the environment in which it is hung, and which has customarily been carefully planned, often at large expense, to produce 40 an artistic effect of which the furnishings 45 form an essential element.

It is the object of this invention to provide a hammock primarily intended for use 40 under these conditions of service and to that end so constructed as to permit the fabric portions thereof to be made of any material desired by the user, or which the particular environment may require, at the 45 same time embodying means and particularly an arm rest of novel construction which are both conducive to the comfort of the user and adapted to enhance the decorative effect and general visual appearance of the device.

50 As a preferred embodiment of means for carrying the invention into effect, that shown in the annexed drawings may be employed and in which,—

Fig. 1 is an end elevation of a hammock 55 embodying the present invention;

Fig. 2 is a transverse vertical cross section on the line 2—2 of Fig. 1, to greatly enlarged scale;

Fig. 3 is a cross section of the device 60 of Fig. 1 taken on a plane just within the windshield member and looking in a direction opposite to Fig. 1;

Fig. 4 is a horizontal cross section through the windshield member on a line such as 4—4, Fig. 3;

Fig. 5 is a view similar to Fig. 1 but illustrating a modification; and

Fig. 6 is a cross section on the line 6—6 of Fig. 5 through the windshield member 70 but to larger scale.

Referring to Figs. 1 to 4 inclusive, a mattress supporting frame of usual construction is indicated as comprising front and rear rails 1, 2, respectively, and side or end rails such as 3. The front and rear rails may if 75 desired be of tubular construction, but it is preferred to form the end rails as angle bars, as indicated in Fig. 2.

This frame serves for the support of a mattress 5 or other suitable cushioning means. 80 Extending upwardly from the frame there may be provided a back rest 6 of usual construction, such back rest being cushioned or upholstered if desired and being secured to the frame by means of links 7 engaging 85 brackets 8 secured to the end members of the frame, the exact arrangement and mode of connection of the back rest being however no part of the present invention.

At 9 is indicated one of a pair of flexible 90 supporting members, herein illustrated as chains, which may depend from a suitably elevated support. At their lower ends these supporting members are preferably provided with enlarged links or rings 10 to 95 which are secured chains such as 11, the opposite ends of which are connected to the back rest whereby to retain the latter in proper position. From the rings 10 also depend pairs of suspension members such 100 as the chains 12, 13, the lower ends of such chains being secured as by means of bolts 14, 15, respectively, to the end bars 3 of the frame. The frame is thus directly supported by the suspension devices comprising 105 the chains 12, 13. In accordance with a preferred arrangement, the chains 12, 13 at points at a proper distance above the cushion 5, but preferably below the upper edge of the back rest 6 are provided with links 16, 110

17 of **S** form, or with other suitable means, whereby an intermediate portion 18 of the chain may be detached. While as herein shown such intermediate portion 18 is of somewhat smaller diameter than the remainder of the chain, it is contemplated that it may be of the same diameter if desired, it being essential, however, that the **S** links be of substantially greater width than the diameter of such intermediate section 18. At each end of the hammock there is provided a bar 19 constituting an arm rest, such bar being provided with vertical openings 20, 21, adjacent its extremities. Preferably such openings are spaced inwardly from the extremities of the bar and are of a diameter to permit the free passage of the intermediate portion 18 of the chain therethrough. If desired the upper surface of the bar 19 between the openings 20, 21 may be provided with a curved surface preferably downwardly concave as indicated at 22, such surface serving as the supporting element of the arm rest and being so curved as to conform more or less closely to the shape of the arm of the user.

In connection with this arm rest there is provided a windshield, preferably comprising a piece of sheet material, such as a textile fabric, which is folded adjacent its central portion, the parallelly arranged members 26, 27 thus formed being united in any suitable manner as for example, by one or more rows of stitches 24, whereby to form a tunnel or hem 25 into which the bar 19 may be freely slipped. With this arrangement it is evident that the parallel members 26, 27, of the windshield thus depend from the bar 19 and upon opposite sides of the plane of the suspension members 12, 13, and in accordance with a preferred arrangement the plies 26, 27 of the material are secured together as by the vertically extending lines of stitches 28, 29, 28^a, 29^a, to form the tunnels or passages 30, 30^a, respectively. The tunnels 30, 30^a so formed constitute convenient means for the reception of such suspension elements, which are thus concealed from view, either from the inside or outside of the hammock, and which are thus provided with a protecting covering which serves to prevent injury to the hands or arms of the user by contact with such suspension devices.

The inner wall 27 of the windshield as thus formed may at its lower edge be provided with a hem, formed by a line of stitches 31, and within such hem there is inserted a substantially rigid bar 32 of a length sufficient to extend beyond the suspension elements 12, 13. By this arrangement the lower portion of the curtain 27 is prevented from bulging out between the suspension elements under pressure against the same from within the hammock. The bar 32 is

arranged at a point such that it lies between the end of the cushion or mattress 5 and the suspension elements, being thus concealed from view. The outer curtain 26 of the windshield device may, if desired, be extended downwardly below the frame to provide a flap or valance 33 which serves to conceal the end of the frame and to give an ornamental appearance to the hammock.

In the ordinary use of the device as thus described, the bar 19 having been inserted in the tunnel 25 of the windshield, the suspension members 12, 13 are passed through the tunnels 30, 30^a, respectively, the intermediate portion 18 of such suspension members passing up through the openings 20, 21, in the bar 19 and being connected to the **S** links 16. As thus arranged the bar rests upon the **S** links 17 which are of a width sufficient to prevent their passage through the openings 20, 21, and the hammock with its windshield and arm rest is ready for use. The direction of the suspension members 12, 13, which diverge from the ring 10 is materially changed at the point where they enter the openings 20, 21, in the bar 19, such bar serving not only as an arm rest but as a spacer member for such suspension elements. It is thus clear that said elements bear with considerable friction against the inner walls of the openings 20, 21, and this friction is ordinarily sufficient to maintain the bar 19 in adjusted position above the **S** links 17 if it be desired, to raise the bar to a height greater than that provided by such links. While as herein disclosed the intermediate portion 18 of the chain is relatively short, it is evident that such portion might be made longer if desired, thus permitting a greater range of vertical adjustment of the arm rest bar 19. This arrangement is very convenient in permitting the use of the hammock by persons of different heights and is also found to be desirable in permitting the raising of the windshield to a more elevated position when the hammock is to be used as a couch and in which case it may be desirable to have the windshield approach in height that of the back rest 6. By supporting the windshield upon the adjustable arm rest it is clear that such shield is adjusted bodily with the arm rest, and as the lower ends of such windshield are both free from attachment, it is clear that such adjustment may readily take place while at the same time permitting the end of the hammock to be fully closed in all positions of adjustment of the arm rest.

If it be found in the use of the device that the friction between the suspension members 12, 13, and the bar 19 is insufficient to retain the latter in the desired position of adjustment, it is clearly evident that bolts or other suitable stop members may be inserted in the chain links at desired points

for retaining the arm in the desired position. It is also clear that so far as the adjustment of the arm rest is concerned, it is unnecessary to employ links of **S** form or other means permitting the detachment of the intermediate section 18 of the chain, as any type of stop means, such as a ring or transversely extending bolt, might serve equally for such purpose. The employment of **S** links is however, desirable in permitting the detaching of the intermediate section 18 of the chain for the removal of the arm rest bar 19 if desired. By removing such bar it is clear that the windshield may be detached and that upon replacement of the bar the hammock may be used with the arm rest but without the windshield, which may be desirable in some cases, as for example in extremely hot weather. It is also clear that both windshield and arm rest may be removed if desired.

Referring to Figs. 5 and 6, the supporting frame is indicated as provided with transverse members such as 1^a and with end members such as 3^a, such frame supporting a cushion or mattress 5^a. The back rest is indicated at 6^a and one of the main supporting chains at 9^a. At 10^a is indicated a ring at the lower end of such supporting chain to which is connected the chain 11^a which serves to support the back rest. To such ring 10^a are also secured the chains 12^a, 13^a, which are secured at their lower ends to the end member 3^a of the frame by means of bolts 14^a, 15^a, respectively. In this case the suspension chains 12^a, 13^a are shown as provided with but one **S** link indicated at 16^a, such link being at a point somewhat below or substantially in the plane of the upper edge of the back rest 6^a. At a convenient point above the mattress 5^a there is provided a bar 40 secured adjacent its opposite ends to the respective chains 12^a, 13^a, as by means of bolts such as 41. The bar 42 is inserted within a fold or hem in a two ply windshield, such fold being secured by means of a line of stitches 43 and the two plies 44, 45 of such windshield depend from the bar 40 and are preferably arranged to lie inside the plane of the chains 12^a, 13^a. The windshield comprising the elements 44, 45 extends downwardly to the plane of the frame, where it is provided with a hem 47 secured by a line of stitches 46. Within the hem 47 there is inserted a bar 48 having openings for the reception of the securing bolts 14^a, 15^a, by means of which the chains 12^a, 13^a are attached to the end member 3^a of the frame. The outer ply 44 of the windshield may if desired be continued downwardly to form the flap 49 which serves to conceal the frame and to give an ornamental appearance to the hammock. An arm rest bar 50 is also provided, such bar having openings 51, 52, respectively, adjacent its op-

posite ends through which freely pass the chains 12^a, 13^a respectively. The bar 50 may rest normally upon the bar 40, being arranged between such bar and the **S** links 16^a, but as in the arrangement previously described, such bar may be adjusted within the limits prescribed by the bar 40 and such **S** links whereby to change its vertical position as respects the mattress. The bar 50 is preferably formed with a curved arm engaging surface 53 and may be covered as indicated at 54 with a suitable material such as textile fabric.

With the arrangement last described it is clear that while the arm rest may be adjusted vertically, the windshield is incapable of such adjustment, and while this arrangement may be desirable under certain circumstances, the preferred form is that shown in Figs. 1 to 4 in which the windshield and arm rest are simultaneously adjustable.

It will be understood that while the suspension elements have herein been illustrated as comprising linked chains, other suitable means for suspending the frame 90 may be employed and it is to be noted that in both the arrangements shown in Figs. 1 and 5 the mattress supporting frame upon which the weight of the occupant rests is supported directly by means of the relatively strong suspension elements 12, 13, and that the windshield need not be of a material strong enough to support such weight. In fact, with this arrangement it is possible to employ relatively thin and light material for the windshield, thus permitting the use of ornamental fabrics, if desired, which could not well be employed were they called upon to support the weight of the hammock and its occupant.

While in general the device has been disclosed as applied to one end only of a hammock it is obvious that the same structure is employed at both ends of the hammock although it is evident that the windshield and arm rest may be omitted or removed from one end without reference to the presence of such devices at the other end of the device.

I claim:

1. A hammock comprising a seat frame, spaced flexible supports therefor, and an arm rest having elements slidably and frictionally engaging the respective supports whereby said arm rest may be adjusted along 120 said supports relatively to the seat frame.

2. A hammock comprising a seat frame, spaced flexible supports therefor, an arm rest of substantial transverse width, said arm rest having openings for the passage 125 of the respective supports and being adjustable therealong relatively to the seat frame, and stop means carried by said supports for positively limiting such adjustment.

3. A hammock comprising a seat frame, 130

- spaced normally converging flexible supports therefor, and a combined arm rest and spreader disposed between said supports to spread them apart and having openings adjacent its ends adapted to receive said supports, whereby said arm rest and spreader is adjustable on said supports and is supported in adjusted position solely by frictional engagement with said supports.
10. 4. A hammock comprising a pair of normally converging and flexible suspension devices, a bar having spaced elements for engagement by the respective suspension devices whereby to maintain the latter in spaced relation, and spaced stop members carried by each of said suspension devices and arranged respectively above and below said bar.
5. A hammock comprising a seat frame, spaced normally converging flexible supports therefor, and a combined arm rest and spreader disposed between said supports to spread them apart and having openings adjacent its ends adapted to receive said supports, whereby said arm rest and spreader is adjustable on said supports and is supported in adjusted position solely by frictional engagement with said supports, and a fabric strip depending from said arm rest and substantially filling the space between said arm rest and said seat frame.
6. A device of the class described having a pair of spaced, normally converging flexible suspension devices, a combined arm rest and spreader bar of substantial width engaging the respective suspension devices and serving to spread them apart, and a wind shield comprising a piece of sheet material having its central portion overlying the bar whereby to provide members depending from the bar for enclosing and concealing the lower portions of said suspension devices.
7. A hammock comprising a pair of suspension members, an end member comprising a bar having elements engaging said suspension members, and a strip of fabric secured to said bar and providing members depending from said bar and arranged upon opposite sides of said suspension members, one of said fabric members terminating in a free end and the other of said members having a pocket and a bar in said pocket.
8. A hammock comprising a seat frame, spaced normally converging flexible supports therefor, and a combined arm rest and spreader disposed between said supports to spread them apart, said arm rest being formed with substantially straight end portions and an intermediate curved portion, the end portions being provided with openings for the reception of said supports.
9. A hammock comprising a seat frame, spaced flexible supports therefor, an arm rest of substantial transverse width and having substantially straight end portions and a downwardly concave central portion, said straight portions having openings for the reception of the respective supports with which the walls of said openings frictionally engage, means for positively limiting movement of said arm rest relatively to said supports, and a wind shield depending from said arm rest.
10. A couch hammock having a supporting frame provided with end members, a pair of chains having their lower extremities secured adjacent the ends of one of said members, respectively, and a spacer bar extending between said chains and provided with apertures for the free passage of the chains therethrough, said chains each comprising enlarged links arranged above and below said bar respectively and constituting limiting stops therefor.
11. A couch hammock having a pair of suspension chains, and a spacer bar therefor provided with spaced openings of a diameter to permit of the free passage of the respective chains therethrough, said chains having S links interposed therein at points adjacent said bar, said links being of a size to prevent their passage through said openings.

Signed by me at Boston, Massachusetts, this 22nd day of April, 1921.

HARRY MINTZ.
